to Van Brede Milling Co., Inc., Clinton, Mass.,
a corporation of Massachusetts

Application November 16, 1953, Serial No. 27,612

Term of patent 7 years

(Cl. D30---5)

To all whom it may concern:

Be it known that I, Roger L. Nowak, a citizen of the United States, residing at West Boylston, Commonwealth of Massachusetts, have invented a new, original, and ornamental Design for a Combined Shipping and Display Tray for Vegetables or the like, of which the following is a specification, reference being had to the accompanying drawing, forming part hereof.

Fig. 1 is a front elevation of a combined shipping and display tray for vegetables or the like, showing my new design;

Fig. 2 is a top elevation thereof;

Fig. 3 is a bottom plan view of the same;

Fig. 4 is a side elevation thereof;

Fig. 5 is a section taken on line 5—5 of Fig. 2;

Fig. 6 is a section taken on line 6—6 of Fig. 5;
and

Fig. 7 is a section taken on line 7—7 of Fig. 5.

I claim:

The ornamental design for a combined shipping and display tray for vegetables or the like, as shown.
